G. F. LYBECK

INTERNAL COMBUSTION ENGINE

Filed May 4, 1926

Inventor
Gunnar F. Lybeck
By Henry D. G. A.S.T.

UNITED STATES PATENT OFFICE.

GUNNAR FREDRIK LYBECK, OF AUGUSTENDAL, NEAR STOCKHOLM, SWEDEN.

INTERNAL-COMBUSTION ENGINE.

Application filed May 4, 1926, Serial No. 106,678, and in Sweden April 15, 1925.

This invention relates to internal combustion engines having one or more pairs of cylinders in which the combustion chambers of each pair are provided with ignition tubes which for starting purposes may be heated externally by a common heating device.

According to this invention the ignition tubes are made readily accessible and removable independently of each other and without necessitating any dismounting of the cylinder by being placed in a laterally through extending space between the combustion chambers of the respective pair of cylinders on opposite sides of the connecting line between the centers of said chambers.

The invention is illustrated in the accompanying drawing, Fig. 1 is a side elevation of the uppermost portion of a two cylinder engine according to the invention. Fig. 2 is a plan view of the engine and, Fig. 3 is a cross section on a larger scale taken on the line A—A, Fig. 2.

The engine illustrated comprises two cylinders 1 having individual combustion chambers 2. The combustion chambers form between themselves a laterally through extending space. In the sides of the combustion chambers facing said space each chamber is provided with an ignition tube 3 adapted to be heated externally, as by a heating lamp when the engine is to be started. To this end the tubes project into said space with their rear parts and are related as closely as possible to each other, yet so that they may be removed independently of each other. To this end they are displaced relatively to each other sufficiently to get free of each other when removed. At the same time care should be taken to place the tubes in a suitable position relatively to the respective combustion chambers and the injecting nozzles thereof.

In the drawing, the ignition tubes are shown as situated side by side in such a way that their center lines will form an angle with the connecting line between the centers of the combustion chambers. If desired, however, they may also be positioned in any other appropriate way, as, for instance, one above the other. In order to utilize in the most efficient way the heat of the heating

device the said space may be covered by a cap 4 having a hole at 5 to enable insertion of the heating lamp or its burner. To still more increase the heating effect a shield 6 may be provided within the cap at that side of the ignition tubes remote from said hole.

The ignition tubes will be freely accessible after removal of the cap 4 and may be unscrewed and removed individually without necessitating any dismounting or removal of the combustion chambers.

What I claim is:

1. In an internal combustion engine a pair of cylinders having individual combustion chambers so arranged as to form a space between themselves, ignition tubes inserted into the walls of said chambers so as to extend with their rear ends into said space, said ignition tubes being so positioned relatively to each other as to enable independent removal and insertion of each tube without necessitating any dismantling of the combustion chamber.

2. In an internal combustion engine a pair of cylinders having combustion chambers so arranged as to form a transversely through extending space between themselves, ignition tubes inserted into the walls of said chambers so as to extend with their rear ends into said space, said ignition tubes being situated of opposite sides of the connecting line between the centers of said chambers.

3. In an internal combustion engine a pair of cylinders having combustion chambers so arranged as to form a transversely through extending space between themselves, ignition tubes inserted into the walls of said chambers so as to extend with their rear ends into said space, said ignition tubes being situated at opposite sides of the connecting line between the centers of said chambers substantially parallel to each other.

4. In an internal combustion engine a pair of cylinders having individual combustion chambers so arranged as to form a space between themselves, a cap covering said space, independently removable ignition tubes inserted in the walls of said chamber so as to extend with their rear ends into said space, said cap having a hole to permit introduction of heating means.

5. In an internal combustion engine a pair of cylinders having individual combustion chambers so arranged as to form a space between themselves, a cap covering said space having a hole formed in it, independently removable ignition tubes inserted into the walls of said chambers so as to extend

with their rear ends into said space, and a shield within said cap behind said ignition tubes as seen from said hole.

In testimony whereof I have signed my name.

GUNNAR FREDRIK LYBECK.
